UNITED STATES PATENT OFFICE.

WILLIAM KLEIN, JR., OF BROOKLYN, NEW YORK.

TRANSFER-TICKET.

SPECIFICATION forming part of Letters Patent No. 763,292, dated June 21, 1904.

Application filed September 16, 1902. Serial No. 123,670. (No model.)

To all whom it may concern:

Be it known that I, WILLIAM KLEIN, Jr., a citizen of the United States, residing in the borough of Brooklyn, county of Kings, and city and State of New York, have invented an Improved Transfer-Ticket for Use in Street-Railways, of which the following is a specification.

My ticket is particularly designed and adapted for use in transferring passengers from one line of cars to intersecting lines, and for this purpose the ticket is composed of a body or main portion and attached coupons having the peculiarities hereinafter described.

15 The accompanying drawing represents my improved ticket.

A indicates the body or main portion of the ticket, and B a series of coupons connected with each other and with the part A. In practice the several parts A and B are joined along lines *a*, which are weakened by perforations or otherwise in a well-known manner. The part A is ruled in narrow columns on each side of a broader central column or space. 25 All of these columns are placed parallel and longitudinally of the part A. In two of the side columns are arranged the numerals "1" to "31," indicating the days of a month, the numerals "1" to "16" being in the column on the left and the numerals "17" to "31" being in the column on the right. On the left of each numeral-column is the time-symbol "A. M." and on the right of such column is the time-symbol "P. M." As shown, these 30 time-symbols occupy columns or spaces which are parallel to those in which the numerals are inscribed. In the central space or column is a dial which is marked to indicate the cardinal points of the compass—to wit, "North," "South," "East," and "West"—and arrows are placed in the center of the dial and point to these words, as shown. Also within such central space is a symbol or numeral designating the particular group or class to which the ticket 35 belongs, and the coupons are similarly marked. In this instance the symbol is "B 1410." In the said central space is also this legend: "This transfers to cars in directions punched only." On each of the coupons B, in addition to the designating numeral or symbol, is

a dial similar in essentials to that inscribed on the body A of the ticket. Each coupon also bears the legend "Not good if detached."

The purpose of my ticket is to prevent a passenger from riding in a circuit on the cars 55 of any street-railway system, and it is an effective check against this. To illustrate its use, suppose a passenger take a north-bound car and after paying his fare he wishes to transfer to another intersecting line going 60 east. He then receives the transfer-ticket substantially as shown in the drawing, and the conductor punches the main ticket directly under the word "North." Each conductor punches the ticket in the direction in 65 which the passenger is traveling and at the same time takes up his coupon. The passenger having transferred to the east-bound line and wishing to transfer to a south-bound line, the conductor on the east-bound line 70 will punch under the word "East," and similarly if the passenger desires to again transfer from south-bound to west-bound train the same transaction takes place—that is to say, the ticket being again punched under 75 the word "South" and another coupon taken up. It is thus possible for a passenger to be transferred as many times as the rules of the company or companies will permit; but he cannot again ride on the same north-bound 80 car as before. Hence he cannot make a circuit or ride twice over the same line or section of the line on the one fare. The body A of the transfer-ticket and the coupon B being numbered alike, the conductor receiving a 85 transfer-ticket with only one coupon detached after the last transfer-point has been passed cannot detach the balance and turn them in as separate transfers in place of cash fares received, since like-numbered coupons, whether 90 detached or in a strip, represent only one transferred passenger. If the transfer-ticket is given in the afternoon, say the seventh day of the month, the conductor punches the ticket A in the "P. M." column directly opposite 95 the numeral "7." On the other hand, if the time be the forenoon, the conductor would punch in the "A. M." column opposite the numeral "7." The day of the month and the division of the day (forenoon or afternoon) are 100

indicated by a single punch. It will be further seen that the arrangement of the numeral-columns and the "A. M." and "P. M." columns parallel and adjacent to the sides of the ticket A enable the conductor to punch a ticket with the greatest ease and rapidity, for not only are the columns easily accessible to the punch, which may be slid along the side of the ticket, but the arrangement is such that the exact point to be punched may be easily perceived without exercising special care.

What I claim is—

1. The improved transfer-ticket composed of a series of connected coupons and a main or body portion all having the same distinguishing-numeral, the said main portion having parallel side columns consisting of numerals "1" to "31," inclusive, indicating the days of a month, parallel columns on opposite sides of the numerals and designated by the time-symbols "A. M." and "P. M.," respectively, and a central space between said numeral-col-

umns which contains a dial marked with the cardinal points of the compass, as shown and described.

2. The improved coupon transfer-ticket comprising the ticket proper bearing the numerals "1" to "31" indicating days of a month, and symbols arranged adjacently for indicating forenoon and afternoon, also the legend "This transfers to cars in directions punched only," the said ticket having a dial with the cardinal points of the compass indicated thereon, and both the ticket proper and the coupons having a like numeral or symbol indicating that the ticket and coupons are parts of one and the same composite ticket, as shown and described.

In testimony whereof I have signed my name to the specification in the presence of two subscribing witnesses.

WILLIAM KLEIN, JR.
